GRID ELECTRODES FOR ELECTRIC DISCHARGE DEVICES

Carl F. Miller, Bath, N.Y., assignor to Westinghouse Electric Corporation, East Pittsburgh, Pa., a corporation of Pennsylvania

Application August 18, 1955, Serial No. 529,302

10

3 Claims. (Cl. 313—350)

This invention relates to electron discharge devices and, 15 more particularly, to a method of fabricating grid electrodes for such electron discharge devices.

In electron discharge devices suitable for use at ultra-high frequencies one of the major problems is keeping the lateral grid wires taut over the complete range of 20 temperatures encountered during manufacture and operation. Because of the very close spacing required in such devices, if the lateral grid wires are loose, troublesome vibrations occur leading to large variations in the characteristic output of the devices. To obtain the necessary 25 very accurate spacings of the cathode, grid and anode assemblies required in ultra-high frequency electron discharge devices, planar grids are frequently used. In fabricating a typical grid electrode of this type, lateral grid wires may be joined to a grid frame member by 30 brazing. If the lateral grid wires and the grid frame member are of different materials, so that the grid frame member has a large coefficient of thermal expansion as compared with that of the lateral grid wires, their different 35 rates of expansion or, in this case, contraction will cause the tautness of the lateral grid wires, which may have been satisfactory at the time of brazing, to be markedly reduced upon cooling. Therefore, at temperatures lower than those encountered during the brazing operation, the lateral grid wires are under less tension and become loose 40 and slack which results in harmful vibrations.

Accordingly, it is an object of this invention to provide an improved method of making grid electrodes for electron discharge devices.

It is another object to provide improved grid electrodes 45 for electron discharge devices in which the lateral grid wires are under tension both during and after the operation of joining the lateral grid wires to the grid frame member.

It is a further object to provide an improved method of 50 joining grid lateral wires to a grid frame member.

These and other objects of the invention will be apparent from the following description taken in accordance with the accompanying drawings which form a part of this application in which:

Figure 1 shows a top sectional view of an electron discharge device embodying a grid electrode made according to my invention;

Fig. 2 shows a top-sectional view of two grid electrodes similar to the grid electrode shown in Fig. 1 after the lateral grid wires have been wound but before the grid electrodes are removed from the mandrel upon which they are mounted during the winding operation;

Fig. 3 shows a front view of a grid electrode during the lateral grid wire brazing operation;

Fig. 4 shows a side view of two grid electrodes in position for the lateral grid wire brazing operation; and

Fig. 5 shows a front view of a grid electrode made according to my invention.

In Fig. 1 there is shown an electron discharge device embodying a grid electrode made according to my invention including a cathode member 11, an anode member

13 and a grid electrode member 15 positioned between said cathode member 11 and said anode member 13. An electron-emissive coating 21 is placed on the portion of the cathode member 11 closest to the anode member 13. The cathode member 11 is heated by a heater member 12 including insulation covered heater wire members 14. The grid electrode member 15 includes a grid frame member 19 and lateral grid wires 17. The elements of this electron discharge device are enclosed in a suitable glass or metal envelope 23.

In Fig. 2 there is shown a top sectional view of two grid electrode members 15 positioned on a mandrel member 25 after the lateral grid wire winding operation. The lateral grid wires 17 have been wound around the mandrel member 25 and the grid frame member 19.

In Fig. 3 there is shown a front view of a grid electrode member 15 during the lateral grid wire 17 brazing operation. Cooling members 29 hold the grid frame cross bar members 31 in position so that heating members 27 may heat the grid frame side members 33 in such a manner as to braze the lateral grid wires 17 to the grid frame member 19. Screw members 35 adjust the tightness of the cooling members 29 upon the grid frame cross bar members 31. The heating members 27 may be radiant burners or electrical heat elements or other suitable heating means. The grid electrode members 15 need not be removed from the mandrel member 25 until after the brazing operation is completed.

In Fig. 4 there is shown a side view of Fig. 3 including cooling members 29, screw members 35, mandrel member 25, and grid electrode members 15. The grid electrode members include grid frame members 19 and lateral grid wires 17. Support members 37 support the cooling members 29.

In Fig. 5 there is shown a front view of a grid electrode member 15 made according to my invention. Lateral grid wires 17 have been joined to a grid frame member 19. The grid frame member 19 includes grid frame cross-bar members 31 and grid frame side members 33.

In accordance with my invention the grid frame member is prevented from expanding laterally during the brazing operation which joins the lateral grid wires 17 to the grid frame member 19. Cooling is a means of preventing the lateral expansion of the grid frame member, and such cooling may be done by the method shown in Figs. 3 and 4 in which the cooling members 29 conduct heat away from the grid frame cross-bar members 31, thereby cooling them. For good cooling, the cooling members 29 should be made of a material having good heat conduction properties, such as copper. The cooling members 29 may be water cooled if necessary. The mandrel member 25 which may be made of molybdenum may also aid in cooling by conduction during the brazing operation.

The brazing operation may be done in a hydrogen furnace to prevent oxidation of the materials involved. The heating members 27 should be positioned close to the grid frame side members 33 and the brazing should be done as quickly as possible. If tungsten lateral grid wires are brazed to nickel plated steel (a suitable steel being SAE 1010 which contains approximately 0.08% carbon, 0.31% manganese and small amounts of phosphorus, sulfur, silicon, nickel, chromium, molybdenum, aluminum and arsenic), a brazing powder composed of 15% silver, 80% copper and 5% phosphorus may be used. The brazing should be done at a temperature of 700° for not more than three minutes. There should be a minimum of five minutes cooling in hydrogen to prevent oxidation when the brazed grid electrode is taken from the furnace. If desired, additional cooling may be obtained by playing a blast of cool hydrogen on parts of the grid frame cross-bar members 31 during the brazing and cooling operations.

My invention allows the outer portions, namely, the grid frame side members 33, to be heated to brazing temperature for a short time, while the central portions, namely, the grid frame cross-bar members 31, are kept at a lower temperature. Therefore, even though the grid frame member 19 is made of a material with a comparatively high coefficient of thermal expansion, the lateral grid wires 17, though made of a material with a comparatively low coefficient of thermal expansion, are not stretched beyond their limit of elasticity because of the small lateral expansion of the grid frame cross-bar members 31 due to their comparatively low temperature during the brazing operation.

If the grid frame cross-bar members 31 were not cooled during the brazing operation and if the grid frame cross-bar members 31 were made of a material having a high coefficient of thermal expansion as compared to that of the lateral grid wires 17, the lateral grid wires 17 very probably would be stretched beyond their limit of elasticity and a permanent set in the lateral grid wires 17 would be introduced or the lateral grid wires 17 might break. As a result the lateral grid wires 17 would be loose and slack at any temperatures below the brazing temperatures. As temperatures which grid frame cross-bar members 31 reach during the operation of a typical electron discharge device of this type are usually considerably below the brazing temperatures, the loose and slack lateral grid wires 17 would cause the troublesome vibrations and large variations in characteristic output mentioned above.

The use of a material for the grid frame member 19 of high coefficient of thermal expansion as compared with that of the lateral grid wires 17, has the desirable effect of keeping the lateral grid wires 17 under tension at temperatures reached during operation.

Suitable materials for the grid frame members 19 having a comparatively high coefficient of thermal expansion include aluminum (coefficient of linear thermal expansion 23.9×10^{-6} per degree centigrade), and its alloys, copper (16.5×10^{-6} per degree centigrade) and its alloys, nickel (13.3×10^{-6} per degree centigrade) or particularly nickel plated steel (SAE 1010 steel 12.2×10^{-6} per degree centigrade). Suitable materials for the lateral grid wires 17 having a comparatively low coefficient of thermal expansion include molybdenum (coefficient of linear thermal expansion 4.9×10^{-6} per degree centigrade) and, particularly tungsten (4.3×10^{-6} per degree centigrade). It is seen that the materials suitable for the grid frame members 19 have a coefficient of linear thermal expansion greater than 10×10^{-6} per degree centigrade and the materials suitable for the lateral grid wires 17 have a coefficient of linear thermal expansion less than 10×10^{-6} per degree centigrade, but suitable materials are not restricted to those limits.

It is also seen that the materials suitable for the grid frame members 19 have a coefficient of linear expansion at least twice that of the lateral grid wires, but suitable materials are likewise not restricted to those limits.

While the present invention has been shown in a few forms, it will be obvious to those skilled in the art that it is not so limited, but is susceptible of various other changes and modifications without departing from the spirit and scope thereof.

I claim as my invention:

1. In the art of manufacturing electron discharge devices, the method of fabricating a grid electrode including the steps of forming a grid frame member having grid frame side members connected by grid frame cross-bar members of a material having a linear coefficient of thermal expansion greater than 10×10^{-6} per degree centigrade, winding wire of a material having a linear coefficient of thermal expansion less than 10×10^{-6} per degree centigrade to form grid lateral wires, placing a cooling

member having a mass substantially greater than that of said grid frame member in heat conductive contact with said grid frame cross-bar members, circulating a cooling fluid over portions of said cooling member, attaching said grid lateral wires to said grid frame side members by the application of heat to a substantial portion of said grid frame side members such that heat energy flows into said cross-bar members, and simultaneously conducting said heat energy from said cross-bar members at a rate such that the temperature differential between said cross-bar members and said grid lateral wires is such that the grid wire laterals are not stretched beyond their limit of elasticity.

2. In the art of manufacturing electron discharge devices, the method of fabricating a grid electrode including the steps of forming a grid frame member having grid frame side members connected by grid frame cross-bar members of a material having a first thermal coefficient of expansion, winding wire materials having a second thermal coefficient of expansion less than said first coefficient of thermal expansion upon said grid frame member to form grid lateral wires, placing a cooling member having a mass substantially greater than that of said grid frame member in heat conductive contact with said grid frame cross-bar members, attaching said grid lateral wires to said grid frame member by the application of heat to substantial portions of said grid frame side members such that a portion of the heat energy flows into said cross-bar members, and simultaneously conducting said heat energy from said cross-bar members at a rate such that the temperature differential between said cross-bar members and said wires exceeds the temperature differential between said grid frame side members and said wires such that the grid wires are not stretched beyond their limit of elasticity.

3. In the art of manufacturing electron discharge devices, the method of fabricating a grid electrode, including the steps of forming a grid frame member having grid frame side members connected by grid frame cross-bar members of a material having a linear coefficient of thermal expansion greater than 10×10^{-6} per degree centigrade, winding wire of a material having a linear coefficient of expansion less than 10×10^{-6} per degree centigrade upon said grid frame member to form grid lateral wires, placing a cooling member in heat conductive contact with said grid frame cross-bar members, heating said grid frame side members to a temperature of about 700 degrees centigrade for a period of not more than three minutes such that a portion of the heat energy flows into said cross-bar members, and simultaneously conducting heat energy from said cross-bar members by means of said cooling member to maintain the cross-bars at a temperature substantially lower than 700 degrees centigrade to thereby reduce the lateral expansion of said grid frame member while providing necessary heat to a substantial portion of said grid frame side members to attach said lateral grid wires to said grid frame member.
